UNITED STATES PATENT OFFICE.

ALEXANDER G. WEISE AND ALBERT F. DIEGLEY, OF CHICAGO, ILLINOIS.

WINDOW-EXTRACTING APPARATUS.

SPECIFICATION forming part of Letters Patent No. 651,682, dated June 12, 1900.

Application filed February 15, 1900. Serial No. 5,301. (No model.)

To all whom it may concern:

Be it known that we, ALEXANDER G. WEISE and ALBERT F. DIEGLEY, citizens of the United States, residing at Chicago, in the county of Cook and State of Illinois, have invented a new and useful Window-Extracting Apparatus, of which the following is a specification.

Our invention relates to improvements in window-extracting apparatus in which the sash are swung from the frame into the room, the object being to facilitate the cleaning or repairing of the windows. We attain this object by the mechanism illustrated in the accompanying drawings, in which—

15 Figure 1 is a closed window in perspective, showing the location ready for use of the different parts of the apparatus. Fig. 2 is a perspective of the upper and lower sash attached together and swung partially out of the frame. 20 Fig. 3 is the hinge. Fig. 4 is the hinge-lug screwed into a portion of the lower sash. Fig. 5 is the suspense peg and lug. Fig. 6 is the jamb-plate. Fig. 7 is the stop button and plate.

25 Like letters indicate similar parts throughout the several views.

In detail, *a* is the frame. *a'* is the jamb. *b*, *b'*, and *b''* are the stops. *c*, *c'*, and *c''* are the parting-strips, and *e* and *e'* are the upper and 30 lower sash, respectively. The stop *b'* is held in place by means of the stop-buttons *g* at each end. This button extends through the stop *b'* and through the stop-plate *h*, attached to the outer surface thereof, thence through 35 the jamb-plate *i* and into the pocket in the jamb *a'*. The head *j* of the stop-buttons *g* is oval-shaped and of a size to correspond with the shape and dimensions of the port *k* in the jamb-plate *i*, and the shank *l* of the button *g* 40 is of such scant length that when the button *g* is turned at right angles with the port *k* the stop *b'* is drawn up snugly and held securely in place, as shown by the broken lines in Fig. 6, but capable of being quickly released 45 and removed when occasion requires.

50 *m* is what we term the "suspense-lug," which is provided with the elongated eye *n* and which is attached by means of ordinary screws to the upper sash *e*, and *o* is what we term the "suspense-peg," which has a flaring base to facilitate fastening by means of ordinary

screws upon the top surface of the lower sash *e'*. The suspense lugs and pegs are placed in such a relative position upon the sash *e* and *e'* that when the upper sash is lowered the 55 eyes *n n* will engage with the pegs *o o*, so as to hold the two sash securely together.

p is what we term the "hinge-lug," having a screw-point and the head of which forms a flange and is adapted to be screwed into the 60 sash *e'*, one near the upper and another near the lower end, as shown.

q is the hinge, one leaf *r* of which is provided with the usual screw-holes and the other leaf *s* is preferably of ornamental design and provided with slots *t t*, which are adapted to engage with the shank of the hinge-lug *p*. One of these hinges is screwed to the stop *b* above each of the hinge-lugs *p* a sufficient distance to afford clearance of the stop 70 *u*, when the sash, by means of the lugs *p p*, should be hung upon the leaf *s s* of the hinges *q q*. The hinges may, if desired, be permanently attached to the sash and the hinge-lugs screwed into the stop. The leaf *s* of the 75 hinge is provided with the slot *t* at each end to facilitate its use in "right" and "left" position. The parting-strip *c''* is permanently held in place by means of ordinary brads in the usual way, while the lower portion *c'* is 80 held in place by means of the upper and lower sash.

The usual or preferable mode of operating our apparatus is as follows: The stop-buttons *g* are released and the stop *b'* removed, the 85 sash *e'* is then raised and hung upon the hinges *q q*, the sash *e'* is then swung slightly ajar, the upper sash *e* is pulled down, and the parting-strip *c'* is removed, after which the sash *e'* is returned and the upper sash *e* is pulled 90 down, so that the suspense-lugs *m m* properly engage with the pegs *o o*, and both sashes so secured together can then be swung so as to present the outer surface of the window to the operator stationed in the room. To return the sash, the inverse order of those steps 95 is observed. The detachable leaf of the hinge is laid back upon the stop to permit passage of the lugs.

Owing to the obvious simplicity of our apparatus the particular industrial utility attributable to it is the facility with which the 100

different parts may be attached and operated upon any old window, the only change necessary to be made in the usual construction of window, old or new, being the cutting of 5 the stop and parting-strip, as above set forth.

Having described our invention, what we claim, and desire to secure by Letters Patent, is the following:

1. In a window-extracting apparatus, the 10 combination with the frame and sash of a number of hinges each formed of a permanently-secured leaf and a portable leaf provided with a slot, a similar number of lugs adapted to portably secure said slotted leaf 15 and a number of perforated lugs secured to one of said sash and corresponding pegs secured to the other of said sash and adapted to engage with each other and hold said sash together, said hinges, lugs and pegs being 20 relatively so arranged upon said frame and sash that when the sash are vertically brought together to clear the horizontal stop the hinges become operatively formed and both sash

will swing out of said frame upon the same hinges, substantially as described. 25

2. In a window-extracting apparatus, the combination with the frame and sash, of the hinges *q*, *q*, attached to the stop *b*, the hinge-lugs *p*, *p*, attached to the sash *e'* and adapted to engage with the hinges *q*, *q*, for hanging and swinging the sash, the suspense-pegs *o*, *o*, upon the upper surface of the sash *e'* and the suspense-lugs *m*, *m*, provided with the eyes *n*, *n*, and adapted to engage with the pegs *o*, *o*, for suspending the sash *e* to the 30 sash *e'* and the stop-buttons *g*, *g*, penetrating the stop and jamb to secure and remove the stop, substantially as described. 35

Witness our hands this 6th day of February, A. D. 1900.

ALEXANDER G. WEISE.
ALBERT F. DIEGLEY.
